United States Patent Office.

WILLIAM H. BURROWS, OF NEW YORK, ASSIGNOR TO JORDAN L. NOTT,
OF MOTT HAVEN, NEW YORK.

Design No. 4,971, dated June 6, 1871.

DESIGN FOR A COOKING-STOVE.

The Schedule referred to in these Letters Patent and making part of the same.

To all whom it may concern:

Be it known that I, WILLIAM H. BURROWS, of the city, county, and State of New York, have invented and produced a new and original Design for the Front and Sides of an Elevated Range, which I term the "St. George," and of which the following is a description, with reference to the accompanying drawings.

Figure 1 represents a perspective view of a range of my design, and

Figure 2 is a central profile section of the same.

Similar letters of reference indicate corresponding parts in both figures.

At the base of the range is a broad fillet, *a*, immediately above which is an ogee, *b*, and above the latter is another fillet surmounted by an ogee, *c*.

The fire-place front *A* of the range is bulged or convexly curved horizontally in the usual manner, and its lower portion conforms to the base molding of the range, and is bounded by two vertical beads, *u u*.

The draught portion of this front is of rectangular form with an arched top, and is bounded with moldings *d*, the form of which is shown more particularly in fig. 2.

Above the fire-place front is the feeder *B*, the door of which is inclined and formed with moldings, whose shape is shown at *f* in fig. 2, and having the words "St. George" formed on it.

On the front of the range, on each side of the fire-place front, and also on each side of the range, are rectangular panels, having arched tops and inclosing a bass-relief figure, *w*, the form of which, and of the moldings *g g* surrounding these panels, is clearly represented in fig. 1 of the drawing.

At the corners of the range are other panels *h h*, which also inclose ornamental figures *x x*, which are represented in the drawings.

The top of the fire portion of the range is bounded by a cavetto, *i*, surmounted by a deep fillet, *j*.

The overhanging lip or portion of the top plate *C* consists of a fillet, *k*, surmounted by an ovolو, *l*.

The back or recessed portion of the range immediately above the top plate has formed along its bottom and sides panels *m m*, inclosing bass-relief ornaments *e**, an ovolو, *y*, surmounted by a bead, *z*, and on its face the shape of which, and of the panel molding, is clearly shown in the drawings.

In the rounded front corners of this portion are sunken panels *n n*, which also inclose ornaments *a**, and are shown in the drawings.

The upper portion of the range which contains the ovens and hot closets is bounded by an ovolو, *o*, and on each side of the oven-doors *D D* is a bass-relief ornament, *p*.

These doors *D D* are bounded by moldings *b**, and have bass-relief figures of St. George and the Dragon formed on them, which, and the shape of the moldings, are clearly represented.

Over these doors is a projecting ledge, *L*, whose edge is formed to constitute a fillet surmounted by two ovolos.

Above this ledge are the doors *E E* of the hot closets, which are bounded by moldings *c**, and have bass-relief ornaments formed on them, which, and the moldings themselves, are clearly represented.

At the sides of the doors are panels *q q*, whose moldings are the same as those of the doors *E E*, and inclose bass-relief figures *d* d**.

Near each side edge of this portion of the range is a bass-relief figure, *r*.

Above this portion is an overhanging top, whose front edge consists of a fillet, *s*, surmounted by an ovolو, *t*.

What I claim as my invention, and desire to secure by Letters Patent, is—

The design for a range, as herein shown and described.

WILLIAM H. BURROWS.
